UNITED STATES PATENT OFFICE.

NELSON WHITE, OF SPRINGFIELD, OREGON, ASSIGNOR TO INTERNATIONAL MONEY MACHINE COMPANY, OF TERRE HAUTE, INDIANA.

MONEY-HANDLING MACHINE.

1,249,869.

Specification of Letters Patent. Patented Dec. 11, 1917.

Application filed September 30, 1915. Serial No. 53,320.

To all whom it may concern:

Be it known that I, NELSON WHITE, a citizen of the United States, residing at Springfield, in the county of Lane and State of Oregon, have invented certain new and useful Improvements in Money-Handling Machines, of which the following is a specification.

This invention has relation to the art of 10 mechanically paying out money. More particularly speaking, the invention comprises certain improvements in that type of money paying machines wherein are employed suitable coin receptacles having ejectors associated therewith, the ejectors being susceptible of selection and operation to cause delivery from the machine of money in amounts predetermined by manipulative keys or the like used to directly control certain 20 selecting mechanism.

In machines of the above type, it is desirable for the purpose of facilitating the delivery of predetermined amounts of money in the smallest number of coins or pieces of 25 money that the selecting mechanism be so designed as to permit of substitution of the delivery of a coin of a larger value, for a plurality of coins of a smaller equivalent value. The present improvements have to 30 do with a means suitable to the above end, the invention being illustrated in connection with instrumentalities whereby upon operation or adjustment of the machine for the paying out of twenty cents and five cents, 35 (in the form of two dimes and a nickel) a twenty-five cent piece will be automatically substituted and delivered. The principle of operation of the instrumentalities just referred to, however, may be employed other 40 than in connection with the particular selection previously mentioned.

In the operation of money paying machines wherein ejectors are utilized to engage and eject coins from suitable receptacles, 45 difficulty has been experienced owing to the fact that under practical working conditions, unless prevented, the ejectors at their coin engaging ends have a tendency to "duck" or drop below the coin or coins engaged on 50 meeting with the resistance naturally offered by such coins which are ordinarily the lowermost ones in the holders of the coin magazine.

Another object of the present invention, 55 therefore, has been to provide positive con-

trolling means insuring absolute accuracy in the delivery operations of the machine by eliminating the liability of defective operation incident to the tendency of the ejectors as above specified. Said controlling means 60 has been designed also with a view of permitting of peculiar dropping of the ejectors as they approach the limit of their ejecting movement so that they may return to normal positions without engaging the coins, or with 65 slight yielding engagement only, a friction eliminating action being thus produced.

All of the foregoing features of construction and operation as well as other details ancillary thereto will be fully comprehended 70 upon referring to the following detail description and to the accompanying drawing, in which:

Figure 1 is a longitudinal sectional view of a money paying machine of the type embodying the present improvements. 75

Fig. 2 is a transverse section taken through the money paying section of the machine.

Fig. 3 is a fragmentary view bringing out more clearly the operating means intermediate the main shaft and the selectors and ejectors. 80

Fig. 4 is a detail view of the ejector locking and controlling devices.

Fig. 5 is a plan view of the same.

Figs. 6, 7 and 8 are similar views in elevation or section bringing out more clearly the various positions assumed by the ejector locking and controlling instrumentalities in performing their functions. 85

Fig. 9 is a plan view showing more clearly the twenty-five cent payment and substituting mechanism.

Fig. 10 is a sectional view of the same.

Figs. 11, 11^a, 11^b, 11^c, and 11^d are detail 95 views of certain of the main and auxiliary selectors involved particularly in the twenty-five cent payment control.

Fig. 12 is a detail view in front elevation of one of the ejector locking plates. 100

General construction of machine.

Referring to Figs. 1, 2 and 3 particularly, the section A of the machine may be termed "the keyboard section of the paying machine" and the section B, "the paying section." The general features of the machine are not material to the present invention because the improvements forming the invention might be readily adapted to many other 110

kinds of paying machines wherein the principle of employing the coin engaging ejectors under suitable selective control is utilized. Having in view the foregoing, only 5 such parts of the machine as are necessary to gain an understanding of the manner in which the ejector mechanism is selected and controlled will be set forth.

As seen in Fig. 1, suitable manipulative 10 keys 29 are employed and are arranged in the manner common in adding machines, according to the decimal system, each row of keys from front to rear including at least 15 keys numbered from "1" to "9" respectively. 15 By depressing a key or keys 29, the lower ends of said keys which contact with lugs 29a on selector bars 1300 are capable of depressing one or more of said selector bars, the form of which is best shown in Figs. 20 11 and 11^a. Suitable locking means is used 25 to hold an operated key or keys depressed, the selector bars 1300 being, at the same time held depressed. Each selector bar 1300 coacts with one or more ejectors 1307, seen best in Fig. 2, the various ejectors being arranged parallel with one another at right angles to the various selectors 1300 which are likewise disposed in parallelism. To 30 communicate movement from the selectors to the ejectors, it is contemplated to provide for each ejector an actuating bail 1371. The bail 1371 is pivoted at 1371^a to suitable plates 1301 and 1371^b in the casing of the machine, one of the legs of the bail 1371 35 being projected downward at 1371^c whereby it forms a lever in engagement with the ejector 1307. Thus it is that if the bail 1371 of a predetermined ejector is shifted pivotally by a selector 1300, said bail will shift 40 laterally the rear end portion of its ejector 1307 until a projection 1307' at the rear end of the ejector engages in a notch at the lower end of an ejector arm 545 on the ejector shaft 615, which shaft 615 is supplied with 45 arms 545 of a number equivalent to the number of ejectors. Each selector 1300 has a projection or projections 1300^a extending from its lower edge to engage one or more of the bails 1371. Thus the selector 1300 50 for eleven cents will have a projection 1300^a to engage the penny ejector 1307 and another projection 1300^a to engage one of the dime ejectors 1307 of which two happen to be provided. Fig. 11 shows the five cent 55 selector designated 1318 having a projection 1318^a equivalent to the projection 1300^a referred to in connection with Fig. 2. Fig. 11^a shows the selector bar 1325 having the projections 1325' to engage the two dime 60 ejectors 1307, for setting the dimes ejectors to pay out twenty cents.

It being understood that a depression of a key or keys 29 will depress coacting selector bars 1300, in Fig. 1 it will be noticed 65 that at the right hand ends the bars 1300

have hooks 48, and these hooks on depression of the bars are engaged with a selector operating bail 47 shown best in Figs. 1 and 3. A main shaft 625 having a handle 625^a thereon is operable to operate the selector 70 bars 1300 as well as the ejector shaft 615. Motion is transmitted from the shaft 625 to the ejector shaft 615 by means of an arm 625^b on said shaft 625 engaging the bifurcation of an arm 515 on the stub shaft 515^a journaled in the left hand side of the keyboard section of the machine. The shaft 515^a carries the arm 515^b provided with the stud 515^c engaged by the hook 542, the latter being supported by an arm 615^b 75 mounted on the right hand end of the ejector shaft 615. A forward movement of the handle 625^a raises the arm 625^b and obviously rocks the several arms 515, 515^b and 615^b, through the connections stated, and thereby rocks rearwardly the ejector shaft 80 615. This operation of the shaft 615 moves forward all of its ejector arms 545, seen in Fig. 2.

Motion is transmitted from the main 90 actuator or handle shaft 625 to the selector bars 1300 which may be depressed by the provision of cam 702 fixed to the shaft 625 and engaging a roller 691 on a lever 523 pivoted at 674 and connected by a link 522 95 with an arm 521 on the shaft 46, to which the bail 47 is secured. Forward movement of the handle 625, therefore, first imparts movement to the selector actuating bail 47 and shortly thereafter to the ejector shaft 100 615, a certain amount of play of the stud 515^c and the hook 542 permitting the previous movement of the selector actuating bail, to insure that the selected ejectors are set before subjected to the operation of the arms 105 545 in connection with which the setting takes place.

Bearing in mind, therefore, that the general operation of the machine is to first 110 depress keys corresponding with a certain amount of money and then causing a forward and rearward stroke of the handle, and that the keys depressed likewise depress their selectors 1300, which will be pulled longitudinally to the right incident to the initial movement of the handle, thereby causing connected ejectors 1307 to be moved at their rear ends to the left and interlocked with the arms 545 of the shaft 615, the operation 115 of the twenty-five cent payment selection 120 may now be set forth.

Twenty-five cent payment selection and ejection.

Referring to Figs. 9, 10 and 11 to 11^a inclusive, Fig. 11 shows the five cent selector or selector bar 1318 and Fig. 11^a the twenty cent selector bar 1325. Figs. 11^a, 11^b and 11^c show certain auxiliary selector and actuating bars numbered respectively 1358, 1356 130

and 1355. The above parts are likewise shown in Figs. 9 and 10 in their proper relative positions. There are utilized in cooperation with the main and auxiliary selector bars above referred to, the actuating bails 1368 and 1369, which unlike the bails 1371, do not directly engage any ejectors but perform a somewhat different function.

For the transaction of paying out twenty cents, the selector bar 1325 (Figs. 11^a and 9) is depressed by the twenty cent key of the keyboard and duly actuated. This bar 1325 merely has two projections 1325' engaging the dimes ejector actuating bails 1371 so that the latter will set the two dimes ejectors to pay out twenty cents, when the machine is operated. In like manner, the nickel ejector 1318 (see Fig. 11) having a single projection 1318', is co-operative by such projection with the nickel bail 1371 to control the nickel ejector.

Suitable means are provided intermediate the selector bars 1318 and 1325 whereby if these two selector bars are simultaneously operated or pulled on by the bail 47, controlling devices are operated which render inoperative the nickel ejector and the two dimes ejectors which are normally controlled and actually moved by said bars 1318 and 1325 when simultaneously operated. Furthermore, the simultaneous movement of the bars 1318 and 1325 is intended to throw into action the twenty-five cent ejector by way of substitution for the two dimes and the nickel ejectors which, as previously stated, are rendered inoperative.

The means just referred to will now be described, it first being understood that the ejector bails 1371 for the dimes and nickel ejectors 1379, seen best in Fig. 10, do not directly engage said ejectors but instead are ordinarily moved so as to draw on springs 1461, directly connected with angle shaped levers 1372 suitably mounted upon a supporting plate in the casing. These levers 1372 are connected at their lower extremities directly with the ejectors 1379 and said levers have tails extending from their pivoted portions, as seen best in Fig. 10.

If, therefore, the twenty cent and five cent keys 29 of the keyboard are depressed, correspondingly depressing the selector bars 1318 and 1325, said bars will be moved longitudinally and simultaneously, incident to the operation of the machine. The projections 1318' and 1325' of the said bars by engagement with the ejector actuating bails 1371 shift said bails to first cause movement of the ejectors 1379 toward positions in which they will be engaged with their arms 545, this being incident to the tilting of the bails 1371 and drawing on the springs 1461. However, the movement of the ejectors 1379, as just described is intercepted by movement of the controlling bails 1310 and

an arm 1373 (see Figs. 9 and 10) these parts being actuated by auxiliary selector mechanism set into motion because of the simultaneous operation of the selector bars 1318 and 1325. The action of the bails 1310 and the arm 1373 intercepting the movement of the ejectors, as previously mentioned is caused by downward extensions of the bails 1310, and the lowermost portion of the arm 1373 moving downward and engaging the tails of the angle levers 1372 whereby to effect a return of said levers to their normal positions and corresponding return of the dime and nickel ejectors to their normal positions spaced from the ejector arms 545. The arm 1373 operates incident to the movement of the adjacent bail 1310 owing to the provision of a link 1374 connecting the operative rear end of the said bail 1310 with the arm 1373.

The means which causes the operation of the bails 1310 and the pivoted arm 1373 whereby as the ejectors 1379 start to engage their ejector arms 545 and then return to normal as so engaging, includes an auxiliary selector 1358 (see Figs. 9 and 11^a) which is pivotally connected at one end with a controlling lever 1360, the opposite ends of which are bifurcated to engage pins 1355^a and 1356^a provided on actuating bars 1355 and 1356 respectively. The bars 1355 and 1356 are normally pulled to the left extremes of their movement by springs and the pins 1355^a and 1356^a engage in bifurcations at the opposite ends of the lever 1360. The lever 1360 is so formed and connected with co-operating members that when either the twenty cent selector bar 1325 or the five cent selector bar 1318 is actuated under the control of its proper key, said lever 1360 is adapted to move freely about its pivotal center without operating the auxiliary selector 1358. The movement of the lever 1360 by the lever 1318 is adapted to be caused by a projection 1318'' (see Fig. 11) on the bar 1318 which projection engages the actuating bail 1368 previously referred to, said actuating bail 1368 having its upper end engaging a projection 1356^a on the actuating bar 1356. The tilting of the bail 1368, therefore, shifts the bar 1356 to the right and shifts the lever 1360 on its pivot owing to the looseness of connection intermediate the bifurcated ends of the lever and the pins 1355^a and 1356^a. In like manner, the movement of the bar 1325 when individually actuated is adapted to be transmitted to the lever 1360 by the actuating bar 1355 (see Figs. 9 and 11^a) the bar 1325 having a projection 1325'' engaging the actuating bail 1369, the upper end of which engages the projection 1355^a on the actuating bar 1355.

The auxiliary selector 1358 seen best in Fig. 11^a, not only operates the bails 1310 and arm 1373 but itself has the projection 1358'' 130

adapted to engage the twenty-five cent bail 1309 (see Figs. 9 and 10) and to operate said bail to throw into action the twenty-five cent ejector simultaneously with the operation of 5 said auxiliary selector to throw out of action the two dimes and nickel ejectors as previously described.

From the foregoing, it will be understood that the auxiliary selector 1358 is not affected by the operation of either one of the main selectors 1318 and 1325 alone, the operation of one of these selectors only, merely creates a pivotal movement of the lever 1360 resulting in no action of the selector 1358, 10 but causing the selecting movement of the bail or bails 1371, of course, and corresponding ejectors depending on whether the nickel or twenty cent selector bar is actuated. If, however, the two bars 1318 and 1325 are 15 selected and operated by depressing the twenty cent key and five cent key of the ten cent and units rows of the keyboard, the synchronous movement of the bars 1318 and 1325 acting likewise on the two bails 1368 and 1369 and the two actuating bars 1355 and 1356, causes all of these parts to be moved to the right, as seen in Figs. 9 and 10, carrying the lever 1360 bodily with them as well as the auxiliary selector 1358. The 20 result is the neutralizing of the preliminary setting movement of the ejectors 1379, in other words, the restoration to normal of these ejectors, and the throwing into operative position of the twenty-five cent ejector 1309 by means of the co-operation of the projection 1358" with the bail 1371 of said twenty-five cent ejector.

It is to be understood from the foregoing that the ejector substituting member herein involved resides primarily in the provision of the main selector bars and an auxiliary selector bar, with connections intermediate the same such that the auxiliary selector bar remains neutral when the main selector bars 45 are separately operated, whereas when said main bars are operated simultaneously the effect of their individual performances is practically negatived and the auxiliary selector bar caused to be operated so as to substitute or act on an ejector different from those controlled directly by the main bars.

It is contemplated that the above principle of operation may be utilized also in paying out of twenty-six, twenty-seven, twenty-eight 50 and twenty-nine cents and all combinations requiring the substituting of a quarter in place of two dimes and a nickel. Furthermore, the twenty-five cent ejector is adapted to be directly engaged by a suitable selector, 55 and operated for paying out thirty, thirty-one, thirty-two, thirty-three, and thirty-four cents, these various amounts being made up of a quarter, a nickel, and certain number of pennies. When paying out thirty-five 60 cents, the principle of the lever connection

1360 between certain main and auxiliary selectors is again utilized. For the thirty-five cent payment, however, involving the operation of the thirty-cent key and the five-cent key, the combined action of the controlled main selectors is to operate an auxiliary selector to substitute a dime instead of two nickels. Since the means for accomplishing this are practically the same as described in regard to the twenty-five cent 75 payment, they are not presented in detail for that reason.

Ejector controlling mechanism.

This mechanism is best seen in Figs. 4 to 8 inclusive upon reference to which figures it will be noted that arranged beneath the front end portions of the ejectors 1307 is the locking plate 1540, the same being of angular formation in that it has a lateral flange at its upper edge cut away to provide a cam portion 1540'. The plate 1540 is secured by suitable fastenings to a rock shaft 1670 mounted in suitable bearings in the frame of the machine. The various ejectors 85 1307 are guided at their front ends by the plate 1301 which has slots through which the ejectors pass, said slots being of sufficient size to permit slight vertical movement of the ejectors. Normally the ejectors are 90 locked by the controlling mechanism in the uppermost positions, as shown in Figs. 4, 6 and 7, and for this purpose levers 1377 are pivoted to the plate 1301, and supplied with rollers 1462 engaging the lower edges of the 100 ejectors, the ends of the levers opposite those carrying the rollers 1462 being formed with cams 1377' adapted to be engaged by the cam portion 1540' of the locking plate 1540. A link 1541 is connected at its front end 105 to an arm 1540" of the locking plate 1540 and at its rear end has a slot receiving a pin 603 projecting from one of the arms 545. Normally the locking plate 1540 is held in the position shown in Fig. 4 by means of a 110 double-nosed catch 1376 pivoted to the plate 1301. As the shaft 615 is rocked incident to pulling forward on the handle of the machine, it will be apparent that the arm 545 connected with the link 1541 will move forward also and when the pin 603 engages the front end of the slot of the link 1541, said link will be shifted slightly forward to rock the shaft 1670. This action takes place as the ejectors 1307, previously rigidly locked 115 or upheld in their upper coin engaging positions by the levers 1377, reach their forward or ejecting limit of movement. The actuation of the rock shaft by the link 1541 disengages the locking plate 1540 from the 120 front ends of the levers 1377, in the manner shown in Fig. 8, and permits the levers 1377 to yield under the weight of the ejectors 1307 whereby the latter will be spaced from the 125 coins or only in slight yielding engagement 130

therewith at the ejecting extremities of said ejectors and may now return to their innermost or normal positions without frictional contact with the lowermost coins in the receptacles 7. As the ejectors approach the limit of their return movement, a lever 1545 pivoted on the ejector shaft 615 has its cam arm 1545' engaged by a stud 687 on the arm 527 (see Fig. 7). The result is that the said lever 1545 is rocked and its lower end being connected by a link 1543 with an arm 1544 on the rock shaft 1670, the shaft 1670 is turned sufficiently to again engage the locking plate 1540 with the various levers 1377. The restoration of the engaging relation intermediate the locking plate 1540 and the levers 1377 raises the said levers 1377 from the position shown in Fig. 8 to that shown in Figs. 4 and 7 and locks the ejectors up raised or in coin ejecting positions owing to the peculiar engagement of the locking catch 1376 with the locking plate as seen in Fig. 4. Suitable springs are connected with the outer ends of the levers 1377 to yieldingly hold the latter in engagement with the ejectors 1307, when the locking plate 1540 is not coöperating with the levers. A spring 1376' is also connected with the catch 1376, see Fig. 4, to maintain the latter in operative engagement with the plate 1540.

By reason of the provision of the controlling mechanism above described including especially the locking plate 1540, it will be apparent that during the preliminary ejecting movement of the ejectors 1307, at which time they must act positively and accurately to make sure of the ejection of the proper coins, it is impossible for said ejectors to "duck" under the lowermost coin or coins of the associated coin holder 70 and the defective operation of such ejectors, previous to the utilization of the controlling means set forth, is thereby obviated.

While in the drawings, a single one of the locking plates 1540 has been illustrated, where the paying section of the machine is of considerable size, more than one of these plates 1540 is actually carried by the shaft 1670. However, all the plates operate in the same manner and are moved simultaneously under such conditions.

Having thus described the invention, what I claim as new is:

1. In a machine for paying out money, ejectors for ejecting separate pieces of money representing a predetermined amount, an ejector for ejecting a single piece of money representing the same in value as the value of the pieces of money adapted to be paid out by the first mentioned ejectors, selecting mechanism controlling said ejectors to operate one or more of the ejectors first referred to and also to operate the last mentioned ejector, and operating means for said selecting mechanism adapted to operate the

ejectors first mentioned to render the same inoperative, and simultaneously render the ejector second mentioned operative as an incident to the said inoperativeness of the first named ejectors.

2. In a money paying machine, ejectors, selecting mechanism controlling certain of said ejectors separately whereby to cause them to pay out predetermined amounts, and including means operable to cause one of the ejectors to pay out a piece of money equivalent in value to those pieces adapted to be paid out by the said separately operating ejectors, the last mentioned means becoming operative when the first named ejectors are operated in conjunction, and operating means for the ejectors.

3. In a money paying machine, the combination of a plurality of ejectors adapted for independent operation, a single ejector, 85 selecting means controlling synchronous movement of the first named ejectors rendering them inoperative and at the same time rendering the said single ejector operative for substitutive action.

4. In a money paying machine, the combination of a plurality of ejectors adapted for independent operation, a single ejector, selecting means controlling synchronous movement of the first named ejectors rendering them inoperative and at the same time rendering the said single ejector operative for substitutive action, and means to operate the several ejectors without the substitutive action above referred to.

5. In a money paying machine, the combination of an ejector actuator, a plurality of ejectors susceptible of independent operation to connect them with the actuator, a single ejector related to those above mentioned, selecting means for operating the first named ejectors simultaneously, and means for connecting the single ejector to the actuator as an incident to the simultaneous movement of the first mentioned ejectors.

6. In a money paying machine, the combination of an ejector actuator, a plurality of ejectors susceptible of independent operation to connect them with the actuator, a single ejector related to those above mentioned, selecting means for operating the first named ejectors simultaneously, and means for connecting the single ejector to the actuator as an incident to the simultaneous movement of the first mentioned ejectors, comprising main selector bars connected with the first ejectors, an auxiliary selector bar connected with the single ejector, a lever pivoted to the auxiliary bar, and connections intermediate the lever and main bars.

7. In a money paying machine, the combination of ejectors, main selector bars controlling certain of said ejectors, an auxiliary

- selector bar controlling an ejector, and a connection between the main and auxiliary bars whereby when the main bars are individually operated the auxiliary bar remains stationary, and whereby operation of the main bars together causes actuation of the auxiliary bar and its ejector to effect a change in the controlling action for the ejectors.
10. In a money paying machine, the combination of ejectors, main selector bars controlling certain of said ejectors, an auxiliary selector bar controlling an ejector, and a lever pivoted to the auxiliary bar and connected with the main bars whereby to be oscillated on its pivot incident to individual operation of the main bars without affecting the auxiliary bar, and means to move the main bars together to impart bodily movement to said lever and thereby operate the auxiliary bar.
15. In ejecting mechanism for money paying machines, the combination of ejectors, means for moving the same longitudinally for ejecting purposes, means supporting the operating ends of the ejectors comprising levers yieldingly coacting with the ejectors, and a locking plate movable into and out of coöperation with said levers to render the latter non-yieldable and yieldable for the purposes specified.
20. In ejecting mechanism for money paying machines, the combination of ejectors, means for moving the same longitudinally for ejecting purposes, means supporting the operating ends of the ejectors comprising levers yieldingly coacting with the ejectors, and a locking plate movable into and out of coöperation with said levers to render the latter non-yieldable and yieldable for the purposes specified.
25. In ejecting mechanism for money paying machines, the combination of ejectors, means for moving the same longitudinally for ejecting purposes, means supporting the operating ends of the ejectors comprising levers yieldingly coacting with the ejectors, and a locking plate movable into and out of coöperation with said levers to render the latter non-yieldable and yieldable for the purposes specified.
30. In ejecting mechanism for money paying machines, the combination of ejectors, means for moving the same longitudinally for ejecting purposes, means supporting the

operating ends of the ejectors comprising levers yieldingly coacting with the ejectors, a locking plate movable into and out of coöperation with said levers to render the latter non-yieldable and yieldable for the purposes specified, said means including a movable arm, a link connected with the locking plate and operable by said arm to throw the locking plate out of coöperation with respect to the levers, and means including a link and lever device for moving the locking plate back into coöperation with said levers.

40. In ejecting mechanism for money paying machines, the combination of ejectors, means for causing ejecting movement thereof, means controlling the coin ejecting action of said ejectors comprising movable supports for the ejectors, a locking plate, means to move said locking plate into coöperation with said movable supports to thereby rigidly hold the ejectors in the path of their ejecting movement, catch means coöperative with the locking plate to maintain the same in coöperation with said supports, and other mechanism coacting with the locking plate to move the same out of coöperation with respect to the supports for the purpose described.

45. In testimony whereof I affix my signature in presence of two witnesses.

50. NELSON WHITE.
